UNITED STATES PATENT OFFICE.

MABEL MILLARD, OF OAK PARK, ILLINOIS.

UNDERGARMENT FOR WOMEN.

957,360.

Specification of Letters Patent. Patented May 10, 1910.

Application filed April 7, 1909. Serial No. 488,440.

To all whom it may concern:

Be it known that I, MABEL MILLARD, a citizen of the United States, residing at Oak Park, in the county of Cook and State 5 of Illinois, have invented certain new and useful Improvements in Undergarments for Women, of which the following is a specification, reference being had to the accompanying drawing.

10 This invention relates to improvements in under garments for women. With some women the catamenial or menstrual discharge is so great that the ordinary napkin or cloth is insufficient to prevent the flow of 15 fluid from escaping beyond it and hence the under and outer skirts of the woman are frequently saturated with such discharge, such saturation often showing through the 20 dress skirt of the woman, thus not only damaging the skirt but causing embarrassment to the wearer.

It is the object of my invention to provide a device having a three-fold object,—namely, 1st, to provide means for holding 25 the usual napkin or cloth more securely in place, 2nd, to provide means for adequately protecting from damage the skirts of the wearer from any over-flow of the fluid from the cloth or napkin, and 3rd, to provide 30 means for holding the skirt-protecting device in proper position and incidentally thereto aiding in supporting the hosiery of the wearer. I accomplish these objects by 35 the construction shown in the drawing and hereinafter specifically described.

That which I claim to be new will be set forth in the claim.

The figure of the drawing shows a perspective view of the device with the parts 40 in the position they will assume when the device is secured to the wearer's body.

Referring to the drawing, 1 indicates a waist-band adapted to be secured around the waist of the wearer, it being provided, 45 as shown, with a tongue and buckle by which it may be tightened up as desired. To the waist-band 1 is secured the upper edge of a depending shield comprising, in the construction shown, a main central portion adapted to conform to the rear of the wearer below the waist line, and side wings or extensions adapted to be brought around the hips of the wearer and depend for some little distance so as to lie against the legs. 55 The shield proper has its main or body portion designated by the numeral 2 and the side wings referred to by the numeral 3.

Formed with the main or body portion 2 is a comparatively long extension 4 which is adapted to be drawn between the wearer's legs. Its free end is provided at its opposite corners with button-holes 5 adapted to receive buttons 6 sewed on the ends of the straps 7. These straps 7, as shown, are arranged diagonally, when in place on the 55 wearer, and are secured at their upper ends by sewing, or in any other suitable manner, to the waist-band 1. By arranging these bands diagonally, the extension 4 is held with its side edges pulled away from each 70 other so as to always maintain that extension as far as possible in the form of a broad band. This extension 4 is adapted to have placed on its under surface the usual napkin or cloth that receives the catamenial or menstrual discharge from the uterus, the portions 2 and 4 forming a saddle for the napkin or cloth, the rear end of which is permanently secured to the rear of the waist-band, the forward end being removably secured to the front of the band by means of the straps 7. Many catamenial sacks on the market have end or side pockets adapted to have such cloth or napkin tucked into them for the purpose of holding them, but such 85 holding means are not ordinarily found as reliable as when the said cloth or napkin is secured in place by safety pins, as is the more common practice with women. I therefore contemplate in the use of my de- 90 vice the securing of the cloth or napkin by safety pins, but inasmuch as the whole protective device shown will ordinarily be formed of a liquid-proof fabric, and as such fabric would be injured by the constant use 95 of safety pins being inserted and withdrawn from it, I provide, as clearly shown in the drawing, two pairs of small holes 8 near opposite sides of the extension 4 and near the free ends thereof, and two pairs of similar 100 holes 9 in the body portion 2, through which holes the attaching safety pins can be inserted. These holes will be protected against being torn open by constant use by sewing their edges as in the case of ordinary button-holes.

To the lower edges of the wings 3, I attach straps 10 which may be shortened or lengthened as desired by buckles, and to the lower ends of these straps I attach ordinary hose- 110

supporters 11. These straps are so located that the hose-supporters will be attached to the hose on the inner sides of the legs. This attachment aids in keeping the side wings in proper position around the upper portions of the legs of the wearer and incidentally affords a support for the wearer's hose.

As will be seen the side wings or extensions are secured respectively to the opposite edges of the saddle, the line of connection extending from the rear of the saddle to a point slightly in advance of the distance between the front and rear of the waist-band along the direction of length of the saddle; said extensions or side-wings are also permanently secured to the waist-band, extending forwardly a distance sufficient to cause the wings to be positioned over the hips of the wearer, but terminating at a point where the material of the wings is sufficient to form a complete closure, the wings each forming an incomplete closure around the legs, the particular form in which the wings are shaped and the manner in which each is connected to the saddle and waist-band shaping the wings to provide a shield which will snugly fit the leg at all portions excepting a portion of the front, the circumferential length of a cross-section of the wings being such as to prevent any overlapping of the free edges of the wings, said edges being permanently spaced apart. By this construction it will be understood that the garment may be placed beneath tightly fitting undergarments without forming a bulging effect or tending to discommode the wearer, being especially applicable for use in connection with the union suits in common use and consisting of a combined corset cover and drawers. Furthermore, the form of the saddle with its ends of increased width, and the connecting of the upper ends of the wings to the waist-band tends to retain the wings in the proper shape when in use, even though the wings be located over the drawers, this construction preventing liability of the parts doubling up or bulging when the wearer is seated. And owing to the permanent spacing of the edges of the wings, it will be understood that the entire wing portion will be brought into snug-fitting contact with that portion of the legs of the

wearer to be protected against the escape of the catamenial flow.

By my invention, I provide a device that enables the usual cloth or napkin to be securely held in proper position to receive the discharge from the uterus, such cloth or napkin being, as will be readily understood from the description, held distended as much as possible by reason of being secured by safety pins passing through the pairs of holes 8 and 9, and the extension 4 being held distended laterally as much as possible by means of the diagonal arrangement of the straps 7. Furthermore, with the rear portion of the body immediately below the waist line and the upper parts of the legs at the sides and rear protected, there is but little danger, if any, of such catamenial or menstrual discharge as escapes past the cloth or napkin coming in contact with the skirts of the wearer. This latter is a very decided advantage over devices now ordinarily used, and particularly so for that large class of women whose monthly discharges are so excessive as to prevent the discharge being wholly retained by the usual cloth or napkin.

What I claim as my invention and desire to secure by Letters Patent is:—

A garment of the class described comprising a waist-band, a saddle secured to the waist-band at its rear and having detachable connection with the band at the front, and side wings permanently secured to the saddle and band, each wing being divided in the direction of its length to provide permanently spaced opposing edges adapted to permit the wings to snugly fit the legs and hips of the wearer, and provide a permanent opening at the front and running lengthwise of the legs of the wearer, said opening extending from the waist-band to the lower end of the wings, the lines of connection of wings and saddle and of the wings and waist-band being of a form to cause the wings to assume a shape in cross-section incompletely surrounding the leg.

MABEL MILLARD.
